UNITED STATES PATENT OFFICE.

CHARLES WHITEFIELD, OF VICTORIA, BRITISH COLUMBIA, CANADA.

PHONOGRAPH REPRODUCER DIAPHRAGM.

Application filed March 25, 1920. Serial No. 363,795.

To all whom it may concern:

Be it known that I, CHARLES WHITEFIELD, a subject of the King of Great Britain, and a resident of Victoria, Vancouver Island, in the Province of British Columbia, Dominion of Canada, have invented certain new and useful Improvements in Phonograph Reproducer Diaphragms, of which the following is a specification.

10 My invention relates to improvements in phonograph reproducers, it being more particularly an improvement in reproducer diaphragms, and it consists in the construction, combination and arrangement substantially as herein described and claimed.

20 One of the foremost objects of the invention is to provide a reproducer diaphragm composed of a plurality of suitably assembled preferably wooden sectors, so treated before assembly, in the manner described below, to confer qualities thereto which enable the diaphragm to render perfect reproductions.

25 A further object of the invention is to provide an improved diaphragm composed of peculiarly treated wooden sectors of suitable number, size and predetermined formation, so mounted on a parchment or like base as to produce a strong diaphragm but one 30 which is capable of cooperating in the reproduction of sounds to a high degree of faithfulness, due to the arrangement and resonance of said wooden sectors.

35 Other objects and advantages will appear in the following specification, reference being had to the accompanying drawing, in which:—

40 Figure 1 is a plan view of the improved reproducer diaphragm, illustrating the arrangement of the wooden sectors and also clearly showing how the grain of the wood converges to the center,

45 Figure 2 is a detail view of one of the wooden sectors,

50 Figure 3 is an end view showing how the sector tapers in thickness toward the center,

55 Figure 4 is a cross section of the diaphragm, taken on the line 4—4 of Figure 1, and

60 Figure 5 is a detail enlarged section of the central portion of the diaphragm illustrated in Figure 4.

The sectors 1 of the diaphragm may be made of any suitable material, but preferably wood. They may also be made in any size required, so that the completed diaphragm may be composed of a greater or lesser number of sectors as particular conditions may require.

65 As clearly shown in Figures 3 and 4, the wooden sectors are thicker at the outer edge 2 than they are at the point 3, in other words, the sectors taper down toward the center where a suitable opening 4 is provided to enable the attachment in any desired manner, of the usual stylus bar of the reproducer. The sectors are assembled and suitably secured to a parchment or like base 5, drum head parchment preferably being employed. The sectors are ozonized in a 70 vacuum, this treatment causing the hardening of the gums of the wood in the pores so that a greater degree of resonance is produced.

75 The sectors are placed in a glass receptacle from which the air is removed by a mechanical air pump. Oxygen is then admitted. A silent discharge is then sent through, creating a large amount of ozone which, combined with the sap, gives to the 80 wood when so treated, a degree of elasticity more than double its ordinary amount.

85 It is further to be observed that the sections are cut from quarter-sawed wood in order that the grain or fiber of the wood may all run to the center of the diaphragm when the sectors are assembled on the parchment base 5. This converging disposition of the fibers is clearly illustrated in Figure 1, this arrangement permitting the sectors 90 to vibrate in unison.

95 While the construction and arrangement of the improved diaphragm as herein described and claimed, is that of a generally preferred form, obviously modifications and changes may be made without departing from the spirit of the invention or the scope of the claims.

I claim:—

1. A reproducer diaphragm, composed of a plurality of sectors, mounted on a parchment or like base, all sectors cross sectionally tapering in thickness toward the center and consisting of quarter-sawed wood to en-

able the convergence of the grain toward the center for uniform vibration.

2. A reproducer diaphragm, composed of a plurality of sectors, mounted on a parchment or like base, all sectors cross sectionally tapering in thickness toward the center and consisting of quarter-sawed wood to en-

able the convergence of the grain toward the center for uniform vibration; said sectors having been ozonized in a vacuum to harden ¹⁰ the gum in the pores of the wood for the production of a greater degree of resonance.

CHARLES WHITEFIELD.
